US00D797112S

(12) **United States Design Patent** (10) **Patent No.:** **US D797,112 S**
Sauvage et al. (45) **Date of Patent:** ** *Sep. 12, 2017

(54) **KEYBOARD LAYOUT FOR A PROTECTIVE COVER**

(71) Applicant: **Logitech Europe S.A.**, Lausanne (CH)

(72) Inventors: **Sylvain Sauvage**, La Tour-de-Peilz (CH); **Malachy Spollen**, Morges (CH); **Alexis Richard**, Morges (CH)

(73) Assignee: **Logitech Europe S.A.**, Lausanne (CH)

(*) Notice: This patent is subject to a terminal disclaimer.

(**) Term: **14 Years**

(21) Appl. No.: **29/519,539**

(22) Filed: **Mar. 5, 2015**

Related U.S. Application Data

(63) Continuation-in-part of application No. 29/443,801, filed on Jan. 22, 2013, now abandoned.

(57) **CLAIM**

The ornamental design for a keyboard layout for a protective cover, as shown and described.

DESCRIPTION

FIG. 1 is a perspective view of a first embodiment of keyboard layout for a protective cover showing our new design;

FIG. 2 is a top plan view thereof;

FIG. 3 is a perspective view of a second embodiment of keyboard layout for a protective cover showing our new design; and,

FIG. 4 is a top plan view thereof.

The broken lines shown represent unclaimed subject matter and form no part of the claimed design.

1 Claim, 4 Drawing Sheets
